(57) **CLAIM**

The ornamental design for a motor shell, as shown and described.

DESCRIPTION

FIG. 1 is a perspective view of a motor shell showing our new design.

FIG. 2 is a front elevational view of the motor shell.

FIG. 3 is a rear elevational view of the motor shell.

FIG. 4 is a left-side, elevational view of the motor shell.

FIG. 5 is a right-side, elevational view of the motor shell.

FIG. 6 is a top plan view of the motor shell; and,

FIG. 7 is a bottom plan view of the motor shell.

The broken lines shown represent unclaimed subject matter and form no part of the claimed design.
